DESIGN FOR A RUBBER OVERSHOE

William Mancik, New York, N. Y., and George H. Quennard, Morristown, N. J.

Application March 30, 1940, Serial No. 91,368

Term of patent 14 years

To all whom it may concern:

Be it known that we, William Mancik and George H. Quennard, citizens of the United States, residing at New York, county of New York, State of New York, and Morristown, county of Morris, State of New Jersey, have invented a new, original, and ornamental Design for Rubber Overshoes, of which the following is a specification, reference being had to the accompanying drawing, forming part thereof.

Figure 1 is a perspective view of a rubber overshoe, showing our new design.

Figure 2 is a side elevational view thereof.

Figure 3 is a top plan view of the same, and Figure 4 is a bottom plan view thereof.

We claim:

The ornamental design for a rubber overshoe, as shown.

WILLIAM MANCIK.
GEORGE H. QUENNARD.
